JACOB H. PAYER, OF PHILADELPHIA, PENNSYLVANIA

JEWEL SETTING TOOL

Application filed January 7, 1930. Serial No. 419,183.

The present invention relates to tools for setting precious stones and more specifically to an improved bead raising tool.

The primary object of the invention is to provide an improved tool of this character serving as a combined tool for raising, shaping and finishing of a round, clean cut bead thru one operation of the graver.

Bead raising tools or gravers as now in common use in the diamond setting trade, are of two general shapes depending upon the individual shape and liking of the user, one shape being a half round and the other a pointed or triangular-shaped tool. In use of both of these types of bead raisers the metal is first raised by cutting a groove in the metal and piling the metal up over the edge of the stone being set. This bead so formed is of irregular shape and whereas a neatly shaped round bead is desired, it becomes necessary to clean and shape the bead. This requires much time and labor. In raising of the bead, the bead will also remain connected at both sides with the metal at the forward end of the groove from which the bead is raised, and these webs must also be moved in the finishing of the bead.

It is therefore a further object of the invention to provide an improved stone setting tool which will greatly expedite the setting of precious stones and at the same time produce a properly shaped bead.

A further object of the invention is to provide an improved tool of this character which while turning the metal over the stone for formation of the bead will sever the metal at both sides of the bead.

A further object of the invention resides in the provision of a tool of this character which thru one operation of the user simultaneously cleans the bead with one stroke in bending it over the stone, resulting in a great saving in time and labor cost.

Other objects and advantages of the invention will be apparent during the course of the following detailed description, taken in connection with the accompanying drawings forming a part of this specification and in which drawings:

Figure 1 is a central longitudinal section thru the improved tool.

Figure 2 is a side elevation of the chuck shown removed from the holder and showing the setting rail in position in the chuck.

Figure 3 is a side elevation of the setting rail.

Figures 4 and 5 are enlarged transverse sections on the respective lines in Figure 1.

Figure 6 is a transverse section on the line 6—6 of Figure 1.

Figure 7 is a side elevation of the improved tool.

Figure 8 is a view showing the manner in which the beads are formed for setting a stone in a mounting.

In the drawings, and wherein similar reference characters designate corresponding parts thruout the several views, the letter A may designate a suitable holder and B the improved setting rail.

The holder A for removably receiving the rail B includes a tubular stem or shank portion 10 being internally threaded at its lower portion as at 11. Secured to the upper end of the shank 10 is a handle 12 preferably provided with a socket 13 for receiving the upper end of the shank. The handle may be secured to the shank by means of a screw 14 threaded into the upper end of the shank 10.

Threaded into the lower end of the tubular shank 10 is a chuck 15 having an externally threaded upper end 16 for threaded engagement with the threads 11. The jaws 17 and which in the example shown are four in number preferably form a tapering lower end 18 above which is formed a tapering shoulder 19. Encircling the intermediate portion of the chuck 15 is a sleeve 20 provided adjacent its upper or inner end with an inwardly projecting lug 21 for fitting in a groove 22 formed longitudinally in the chuck 15 and opening at the inner end of the chuck. The inner end of the sleeve 20 has a bearing fit against the lower end of the stem 10 and the outer end of the sleeve is flared outwardly as at 23 for engagement with the tapering shoulder 19 whereby the jaws 17 are moved into gripping engagement with the rail B. The lug 21 prevents rotation of the chuck 15 when the shank 100

10 is rotated for opening and closing the jaws 17. The chuck 15 has an opening 24 extending entirely therethru for receiving the rail B and this opening is preferably of a shape conforming to the cross sectional shape of the rail B.

5 The rail B is of channel-like formation in cross section thruout its length with the inner or concaved side of the channel being of U-shape providing a rounded bottom 26. The 10 outer surface of the rail is of substantially V-shape and formed with the arcuate surfaces 28 merging into a sharp base edge 30. The outer or working end of the rail is beveled off as at 32 thus forming a working end for cutting and turning the metal.

One of the chuck jaws is formed thruout its length and along the opening 24 with a rib 34 of a shape to snugly fit within the channel of the rail B. The jaw diametrically opposite to the jaw provided with the rib 34 may be provided along its inner side with a suitable groove 35 conforming to the external shape of the rail along the base edge 30. This rib 34 extends beyond the lower or outer end of the jaws 17 as shown at 36 in Figure 2 and terminates a short distance inward from the beveled working end 32. This extending rib portion 36 acts as a reinforcement for the projecting portion of the rail B and allows the rail to be extended a sufficient distance beyond the chuck so that a clear view may be had of the work being operated upon. Since the rail B in actual practice will have a cross sectional dimension of about $1\frac{1}{8}$ ", it 20 will readily be seen the desirability of having the reinforcing extension 36 extended to a point relatively close to the working end of the rail. By having the rib 34 engage the rail 25 for a substantial portion of its length allows for the chuck to tightly grip the rail. This tight gripping of the rail by the chuck is necessary owing to the fact that when the rail is in use, considerable pressure must be applied to the rail in both a forward direction and sidewise when molding the bead.

In Figure 8 has been illustrated an example 30 of the use of the tool for setting a stone D in a mounting designated by the letter E. With use of the tool, having the channel-shaped rail, the beads C may be raised, cleaned and shaped with one operation. In use of the improved tool, the metal of the mounting D is grooved as at 50 thru movement of the 35 working edge 32 toward the stone D. This movement of the tool toward the stone raises the metal forming the beads C and after the groove 50 has been cut for a proper distance from the stone the tool is swung upwardly at an angle over the stone thus turning the metal 40 over the stone to form the bead C. Rounding of the bead is simultaneously being effected while raising the bead, by the rounded bottom 26 along the inner side of the rail. As the 45 rail is tilted over the stone, the sides of the

beveled ends 32 will cut into the metal at both sides of the beads at the inner ends of the groove 50 thereby separating the beads except for a portion at the bottom of the groove 50 and presenting a clean cut rounded bead. Thus it will be seen that with a forward movement and then a rocking movement of the rail over the stone that a clean cut round bead will be formed not requiring further cleaning and shaping.

70 While the specific cross sectional shape of the channel-shaped rail B has been shown as having a substantially U-shaped inner contour and of V-shape at its outer surface, the sectional shape of the rail may be varied 75 slightly so long as the rail is substantially channel-shape or provided along one side with a suitable groove. The rails will also be made of different sizes for the purpose of raising large and small beads. It is also to 80 be understood that any preferred type of holder may be substituted for the holder A and that means other than a chuck as shown may be employed for adjustably gripping the rail.

90 As the rail B becomes worn thru use and resharpening of the working end 32, the chuck may be released and the rail fed outwardly thru the chuck to the desired position found most practical for the individual user. The 95 hollow shank 10 permits of the holder accommodating a relatively long rail.

99 From the foregoing it will be apparent that an improved bead raising tool has been disclosed whereby the bead being raised is 100 cleaned with a single stroke in bending the bead over the stone being set and thereby eliminating the costly cleaning and shaping operations ordinarily required with the present types of bead raising tools to produce a 105 high grade piece of work. It will also be apparent that the specific formation of the rail makes it possible for the single tool to be used for raising, forming and cleaning of the beads thru a forward and then a rocking 110 movement of the tool in bending the bead over the stone. A novel construction has also been disclosed whereby the rail is rigidly held against movement during use of the tool.

115 Changes in detail may be made to the form of invention herein shown and described, without departing from the spirit of the invention or the scope of the following claims.

I claim:

120 1. In a bead raising tool, a rail of channel-shape cross section and having a beveled working end, and a holder for the rail embodying a tubular stem, and a chuck carried by the lower end of the stem and thru which the rail extends into the tubular stem, said 125 chuck having a rib formed longitudinally along the inner side of one jaw thereof for engaging in the channel side of the rail.

130 2. In a bead raising tool, a channel-like rail having a beveled working end, and a

holder for the rail embodying a tubular stem, a chuck threaded into the lower end of the tubular stem and having a passageway longitudinally therethru, said chuck embodying 5 yieldable jaws for clamping engagement with the rail, and a rib formed along the inner side of one jaw for fitting in the channeled side of the rail.

3. In a bead raising tool, a channel-like 10 rail having a beveled working end, and a holder for the rail embodying a tubular stem, a chuck threaded into the lower end of the tubular stem and having a passageway longitudinally therethru, said chuck embodying 15 yieldable jaws for clamping engagement with the rail, and a rib formed along the inner side of one jaw for fitting in the channeled side of the rail, said rib projecting beyond the end of the chuck to a point adjacent the beveled 20 working end of the rail.

4. A bead raising tool comprising a channel-shaped rail having a beveled working end, a holder for the rail embodying a chuck thru which the rail extends with the working 25 end projecting beyond the outer end of the chuck, and a rib formed inwardly of the chuck for fitting in the channel-side of the rail and projecting beyond the outer end of the chuck.

30 5. A jewel holding prong raising and forming means comprising a rail of channel-shape in formation and having a beveled working end, said rail in cross section being substantially U-shaped at its inner side and substantially 35 V-shape at its outer surface to produce a penetrating point while maintaining a forming curve at its inner side.
